UNITED STATES PATENT OFFICE.

DANIEL P. BOYLE, OF NEW YORK, N. Y.

WRITING DEVICE.

Application filed April 9, 1924. Serial No. 705,165.

The object of my invention is to provide a simple, inexpensive, strong and efficient mechanical pencil construction, adapted particularly for a combination fountain pen and pencil article.

In the accompanying drawings forming a part hereof, illustrating the preferred embodiment of the invention:

Fig. 1 is a side elevation of a combination fountain pen and pencil embodying the invention;

Fig. 2 is a longitudinal section on a larger scale, taken through the pencil part and the rear portion of the fountain pen barrel;

Fig. 3 is a side elevation looking at right angles to Fig. 2, with the case of the pencil and the lead-chamber removed, no lead being shown in the lead-propeller;

Fig. 4 is a side elevation of the pencil case and lead-chamber, removed, illustrating the manner of inspecting the leads in the lead-chamber; and

Fig. 5 is a cross-section on the line 5—5 of Fig. 2.

The numeral 2 designates a fountain pen barrel, which contains the ink bag 3 for supplying the pen 4. 5 is a cap formed to cover either the pen, as in full lines in Fig. 1, or the pencil, as indicated in dotted lines. The rear end of the barrel 2 is formed with an extension 6 containing a socket. In this socket is fixed a bushing 7, in which in turn is fixed the rear end of a tube 8, which extends endwise from the barrel. The tube 8 constitutes a lead-propeller guide, which may be fixed to the barrel in other specific ways, though the manner illustrated is preferred. This tube is provided with a longitudinal guide slot 9, through which projects a kink 10 on a hooked wire 11, which carries a lead-tube 12 and centers it in the tube 8. The lead *a* is held by friction in the tube 12, so that the lead is both propelled and retracted. The kink or follower projection 10 cooperates with a spiral guide 13, which is fixed in the case 14 of the pencil. Rotation of the case causes the lead-propeller to travel along the spiral groove, in order to advance or retract the lead, according to the direction of turning.

The guide tube 8 is extended forward within the tapered forward portion 15 of the case, and is contracted at its forward end 16 to form an inner guide support for the lead behind and near the tip guide 17 of the case.

The rear end of the case 14 extends with-

in the socket 6, wherein it can be rotated and from which it can also be withdrawn. The case is held to the barrel by a detachable connector sleeve 18. In the preferred construction the rear end of this sleeve is internally screw-threaded, in order to screw on and off screw-threads 19 on the reduced end of the barrel extension 6. The forward end of the sleeve has an inturned flange 20, which has swivel engagement with a circular groove 21, affording shoulders both inside and outside of the flange, preventing longitudinal separation between these parts in either direction. The sleeve 18 projects for a substantial distance over the case 14, and is spaced therefrom, except at the flange, so as to form an annular lead-chamber 22, which is closed at the forward end by the flange. Spacing projections 23, forced out from the case 14, keep the sleeve and the case in concentric relation when these parts are removed, as shown in Fig. 4. The rear end of the case projects beyond the rear end of the sleeve, so that the leads can be brought to view by placing the finger against the end of the case and holding the pencil case with its rear end down, as shown in Fig. 4.

The operation of the illustrated pencil mechanism, to which I do not necessarily limit myself, will be readily understood. In order to remove a stub of lead from the tube 12 of the lead-propeller, the entire lead-propeller 11, 12 can be withdrawn through the slot. A fresh lead is inserted into the lead-propeller through the inner guide 16. Such reloading is accomplished when the case 14 has been removed, exposing the internal parts, as seen in Fig. 3.

While the preferred embodiment of the invention has been described in detail, it will be understood that there may be numerous changes in respect to details, reversals, additions, omissions and substitutions.

What I claim as new is:

1. In an article of the character described, a barrel having a socket in its end, a lead-propeller guide having its rear end fixed in said socket, a lead-propeller guided in said guide, a rotatable case containing a second guide cooperating with the lead-propeller, one of said guides being a spiral, the rear end of said case being accommodated rotatably and removably in said socket, and a detachable connector sleeve retaining the case to the barrel.
2. In an article of the character described,

a barrel, a slotted lead-propeller guide extending in fixed relation from the end of the barrel, a lead-propeller guided in said guide, a removable and rotatable case enclosing said slotted lead-propeller guide and lead-propeller and containing a second guide cooperating with the propeller-guide, one of said guides being a spiral, and an external detachable connector sleeve retaining the 10 rear end of the case to the barrel.

3. In an article of the character described, a barrel, a slotted lead-propeller guide extending in fixed relation from the end of the barrel, a lead-propeller guided in said 15 guide, a removable and rotatable case enclosing said slotted lead-propeller guide and lead-propeller and containing a second guide cooperating with the propeller-guide, one of said guides being a spiral, and an external connector sleeve having means of detachable connection with the barrel and extending over the rear end of the case and 20 cooperating with a shoulder thereon.

4. In an article of the character described, a barrel, a slotted lead-propeller guide extending in fixed relation from the end of the barrel, a lead-propeller guided in said 25 guide, a removable and rotatable case enclosing said slotted lead-propeller guide and lead-propeller and containing a second guide 30 cooperating with the propeller-guide, one of said guides being a spiral, and an external connector sleeve having means of detachable connection with the barrel and extending 35 over the rear end of the case and having a flange at its forward end which engages the case in such manner as to couple these parts against separation in either and both directions.

5. In an article of the character described, a barrel, a lead-propeller guide extending in fixed relation from the end of the barrel, a lead-propeller guided in said guide, a removable and rotatable case containing a 40 second guide cooperating with the propeller-guide, one of said guides being a spiral, and a detachable connector sleeve retaining the 45

case to the barrel, said sleeve being removable with the case and there being a lead-chamber between them.

6. In an article of the character described, a barrel, a lead-propeller guide extending in fixed relation from the end of the barrel, a lead-propeller guided in said guide, a removable and rotatable case containing a 50 second guide cooperating with the propeller-guide, one of said guides being a spiral, and a detachable connector sleeve retaining the case to the barrel, said sleeve having a swivel coupling with the case and forming 55 therewith an annular lead-chamber.

7. In an article of the character described, a barrel, a lead-propeller guide extending in fixed relation from the end of the barrel, a lead-propeller guided in said guide, a 60 removable and rotatable case containing a second guide cooperating with the propeller-guide, one of said guides being a spiral, and a detachable connector sleeve retaining the case to the barrel, said sleeve having a swivel 65 coupling with the case and forming therewith an annular lead-chamber, the rear end of the case forming the inner wall of the lead-case extending beyond the rear end of the sleeve forming the outer wall of the 70 case.

8. The combination with a barrel, of a mechanical pencil extending endwise from the barrel and including a rotatable case, and a connector sleeve having means of detachable connection with the barrel and swivel connection with the case, and forming a lead-chamber around the rear part of the case.

9. The combination with a barrel, of a mechanical pencil extending endwise from the barrel and including a rotatable case, and a connector sleeve having means of detachable connection with the barrel and swivel connection with the case, and forming a lead-chamber around the rear part 80 of the case, together with spacers between the case and sleeve.

DANIEL P. BOYLE.
